SAFETY RAZOR

Joseph Muros, Cambridge, Mass., assignor to Gillette Safety Razor Company, Boston, Mass., a corporation of Delaware

Application March 3, 1944, Serial No. 524,944

3 Claims. (Cl. 30—65)

This invention relates to safety razors and consists in a new razor-and-blade combination which includes as one of its elements a thin, flexible open-end blade.

Open-end razor blades, that is to say, blades having a medial slot opening out through one of their transverse end edges, may be employed in safety razors in which the cap and guard members are detachably connected, and such blades have also the additional advantage that they may be presented edgewise in any safety razor wherein the cap and guard members are connected to permit only a limited separation and are not completely detachable. Such razors are preferred by many users because they include no loose parts likely to be lost or mislaid in use.

It has been found that in safety razors of the type wherein the blade is transversely flexed when it is clamped in shaving position, as in the "Gillette" type safety razors, the cutting edges of an open-end blade are frequently deflected out of their normal parallel relation. Whereas, the two sharpened longitudinal edges may be disposed accurately in parallel relation when the outline of the blade is initially determined, the two edges are often found to diverge toward the open end of the blade when the blade is flexed and clamped in the razor. This is due partly to the fact that the hinge portion at the closed or solid end of the blade has a restraining effect on the two side portions which is entirely absent at the open end of the blade. Going more into detail, the side portions are tied together at the closed end of the blade by a flexible connection which, when curved by the cooperating clamping elements of the razor, causes the cutting edges of the blade to draw together. However, inasmuch as the side portions of the blade adjacent to its open end are free and unconnected the free ends are not subjected to this drawing-in action. These differences in structure and behavior, and possibly other causes, often result in a departure from parallelism of the two sharpened cutting edges in an open-end blade when finally clamped in shaving position. Such variation detracts from the precision of the assembled razor and produces irregularities in the edge exposure of the blade that may even become so excessive as to be dangerous in some cases.

I have discovered that uneven edge exposure in open-end blades may be eliminated by a novel razor-and-blade combination, that is to say, by combining a flexible open-end blade with a razor having cap and guard members of such configuration that the interposed blade is flexed both

transversely and longitudinally between them. When such combined flexing distortion is impressed upon a flexible open-end blade it results in a converging movement or tendency at the free end of the blade, narrowing the medial slot and compensating for any objectionable spreading tendency which might otherwise occur in the side portions of the blade.

Having made this discovery, I go a step farther and provide in the razor structure an abutment or stop having oppositely disposed gauging faces arranged to be placed in the slot of the blade at its open end and to arrest the converging movement of the free ends of the blade when that movement has progressed to the point at which the sharpened outer edges of the blade lie exactly parallel to each other. Thus, without any modification in the structure of the open-end blade itself, I am able to insure a compensating closing-in movement when the blade is clamped preparatory to use and to obviate all the disadvantages which otherwise appear to be unavoidably associated with open-end blades.

These and other features of the invention will be best understood and appreciated from the following description of a preferred embodiment thereof selected for purposes of illustration and shown in the accompanying drawing, in which:

Fig. 1 is a view in perspective of the complete razor;

Fig. 2 is a view of the razor in longitudinal section and on an enlarged scale;

Fig. 3 is a view in perspective of the various parts of the razor in exploded relation.

The razor herein selected for purposes of illustration is similar to the well-known "Gillette" safety razor except that its cap and guard members are shaped to present complementary longitudinal curvatures instead of being straight in that sense as heretofore. The amount of this longitudinal curvature is very slight as indicated in the double-size view of Fig. 2 by the departure of the dot-and-dash line from the medial surface line of the cap member. By a slight departure from the straight line, I mean a departure in the order of $\frac{1}{2}$ " or less.

The guard member 10 as shown in Fig. 3 is rectangular in outline and generally convexed upwardly, having spaced parallel fulcrum shoulders 11 over which the blade is flexed in use. The guard member is flanged downwardly at its longitudinal edges to provide parallel guard bars 12 and provided centrally with a diamond-shaped recess 13. In the centre of the bottom of the depression 13 is provided a circular aperture 14

through which passes with clearance the threaded stem 19 of the cap.

The cap member 16 has a concave blade-engaging face and is somewhat wider between its longitudinal edges than the spacing of the fulcrum shoulders 11 of the guard member so that the cap may flex an interposed blade over the fulcrum shoulders 11. It is provided in each of its corners with a downwardly projecting reinforcing lug 17. In its longitudinal medial axis lies a blade-locating rib 18 which is to form the abutment or blade-stop as will be presently described. Centrally disposed with respect to the rib 18 is a downwardly extending threaded stem 19, having a flattened section near its inner end that does not exceed the thickness of the rib so that the slotted blade may pass in this flattened section when introduced endwise beneath the cap. A tubular handle 20 is threaded to fit the stem 19.

One of the many open-end types of blades adapted for use with the razor above described is shown in Fig. 3 and comprises an elongated body 22 separated into two side portions by a medial slot 23 opening out through the left-hand transverse edge of the blade. The two side portions are connected at the right-hand side of the blade by a transverse hinge portion 24 which, although slightly annealed in the process of manufacture, retains almost the same temper and resiliency as the remainder of the blade. The slot 23 has various intermediate enlargements designed to fit the blade-locating projections of razors in which it may be used and also a central circular aperture to receive with clearance the threaded stem 19 of the cap member. The various parts shown in Fig. 3 are assembled by passing the stem 19 through the blade, through the aperture provided for this purpose in the guard member and screwing the handle 20 tightly up upon the stem, or if the cap and guard are not completely detachable the blade may be presented endwise, straddling the rib 18.

As the cap and guard members are drawn together in clamping the blade between them, the blade is transversely flexed over the fulcrum

shoulders 11 of the guard member by the edges of the cap 16. At the same time a longitudinal curvature or bowing is imparted to the blade by the complementary longitudinal curvature of the safety razor parts. It is this secondary or longitudinal curvature that tends to draw together the free ends of the two sharpened side portions of the blade 22. This drawing together of the blade portions continues until the inner edges of the blade slot 23 bring up against the oppositely disposed faces of the blade-locating rib 18. When this occurs, as already explained, the sharpened cutting edges of the blade have been positioned exactly in parallel relation and any spreading tendency or failure to maintain parallel relation has been thus compensated for and eliminated entirely in the clamped razor.

Having thus disclosed my invention and described in detail an illustrated embodiment thereof, I claim as new and desire to secure by Letters Patent:

1. The combination of a razor having cooperating blade-clamping members shaped to flex transversely a thin blade interposed between them and conformed in complementary longitudinal curvature, with an open-end flexible blade flexed between said members and thereby drawn together at its open end.

2. The combination of an open-end razor blade, with a razor comprising cooperating blade-clamping members having opposed faces transversely curved and also longitudinally curved, thereby imparting a closing-together tendency to the open end of the blade.

3. The combination of a double-edged razor blade having a medial slot opening through one of its end edges, with a razor comprising a blade-supporting member having parallel fulcrum shoulders, and a cap member having a transversely curved blade-engaging face for flexing the blade over said shoulders, both of said members being shaped to impart also a longitudinal curvature to the blade and thereby contract its open end.

JOSEPH MUROS.
